LOCOMOTIVE TENDER

William C. Peyton, New York, N. Y., assignor to
 The Standard Stoker Company, Incorporated, a
 corporation of Delaware

Application July 30, 1932, Serial No. 626,288
 Renewed February 21, 1935

33 Claims. (Cl. 198—15)

This invention relates to locomotive tenders of the class equipped with stoker mechanism. The primary object is the provision of an unusually long tender of the character described.

In past practice, most of the tenders for stoker fired locomotives were provided with a cast steel screw conveyor mounted in an open mouth trough for advancing the fuel from the bunker to a conveyor leading forwardly from the tender to the locomotive. The length of the cast screw permissible with satisfactory operation is an important factor in the design of tenders, particularly so on those transportation systems where the trend of the design is toward the adoption of longer tenders with greater fuel carrying capacity than those now in service. One design considered contemplates the use of a stoker conveyor approximately 25' long which is about double the length of the conveyors of past use. Many problems apparent to those skilled in the art arise in connection with the use of such a conveyor.

This invention seeks to meet the problems by the provision in a locomotive tender of a stoker conveyor comprising a plurality of sections disposed under the fuel bunker and arranged with the delivery end of one of the sections being positioned above the receiving end of another. In one embodiment of the invention, as will presently appear, the stoker conveyor of the aforesaid construction is adapted for use with a fuel bunker having a plurality of discharge outlets disposed in different elevations.

Many specific objects and advantages of the invention will be apparent from the following description when read with the accompanying drawings, in which,

Fig. 1 is a vertical longitudinal central sectional view of the locomotive tender of the invention;

Fig. 2 is an enlarged vertical transverse section taken on line 2—2 of Fig. 1;

Fig. 3 is an enlarged vertical transverse sectional view taken on the irregular line 3—3 of Fig. 1;

Fig. 4 is a view similar to Fig. 1 representing a modified form of the invention;

Fig. 5 is a vertical transverse section taken on the irregular line 5—5 of Fig. 4; and

Figs. 6, 7, 8 and 9 are enlarged vertical transverse sectional views taken on lines 6—6, 7—7, 8—8 and 9—9, respectively, of Fig. 4.

On the drawings, Figures 1 to 3 inclusive, illustrate the invention embodied with a tender of the type wherein a separate compartment under

the bunker is provided to receive the stoker conveyor. For purposes of description, this construction will be referred to as the preferred embodiment of the invention, although the structure illustrated in Figures 4 to 9 inclusive, may be preferred in service because additional water space is provided by placing the stoker conveyor as shown within the water compartment.

Referring to Figures 1 to 3, the improved tender as a whole is represented at A. It includes 10 the underframe 10 above which is formed the water compartment 11 and the fuel bunker 12 separated by the rear and side partition plates as at 13 and 14 respectively. Extensions 13a and 14a of the rear and side partition plates form 15 with the imperforate wall 15 of the underframe, a stoker conveyor compartment 16. This compartment is separated from the fuel bunker by the horizontally disposed floor 17 consisting of rearward and forward sections 17a and 17b re- 20 spectively, which are arranged in different elevations. Preferably, the rearward floor section is positioned in a horizontal plane above the forward floor section. Their adjacent ends are connected by an upstanding wall 18 extending 25 transversely thereof. Suitable brackets as at 19 and 20 support the floor sections from the partition walls 14a.

The floor sections are centrally apertured at 21 and 22 respectively. The two constitute a downwardly opening discharge outlet in the bottom of the bunker. From another aspect of the invention, the apertures 21 and 22 may be considered as fuel bunker discharge outlets disposed in different elevations. Discharge of fuel through the 35 apertures or bunker outlets, is controlled by slide-able plates 23 which are well known in practice, but which never before have been disposed in series arranged in different elevations. The slide-able plates of the forward floor section 17b are 40 carried in the seat 24 formed by any suitable construction of plates or bars on the underside of the floor; and similarly, the slideable plates of the rearward floor section are carried in the seat 24a. The plates are pulled forward one at 45 a time to provide what may be called a shiftable opening as at 22 in Figure 1. As the fuel recedes in the bunker the rearward plates are pulled forward in succession.

It will be observed that the forward slide plate 50 23a of the rearward floor section 17a when pulled forward hangs over the wall 18 and rests in an inclined position upon the rearmost plate of the forward floor section. A lug 25 depending from the forward slide plate 23a engages the wall 18 55

and restrains further continued forward movement of the plate and its acts also to maintain the plate in the inclined position as shown conventionally in Figure 1.

5 Fuel passing through the bunker discharge outlet is received by a stoker conveyor indicated as a whole by the letter S. This conveyor is mounted in a fixed position on the underframe 10 beneath the fuel bunker 12 in the conveyor compartment 16. It may be formed of any desired number of 10 offset sections, but preferably, it comprises the rearward section 26 and the forward section 27. These sections are made in the form of troughs, as best shown in Figures 2 and 3, and are disposed 15 with the delivery end portion 26a of the rearward trough section positioned above the receiving end portion 27a of the forward trough section. The trough sections are shown disposed in horizontal planes one higher than the other, but it will be 20 recognized the one or both of them may be placed in an inclined position if desired.

Preferably, the rear trough section 26 is mounted closely adjacent and directly beneath the bunker floor section 17a, and similarly, the forward trough section 27 is disposed under the forward floor section 17b. The adjacent ends of the trough sections are offset from one another and the rearward trough section is provided with the downwardly opening passage 28 communicating with the receiving portion 27a of the forward trough section at a point rearward of or directly adjacent to the wall 18 between the bunker floor sections.

In this embodiment of the invention the trough sections are constructed as separate units with the section 27 carried by the underframe 19 and the section 26 secured in an elevated position to the floor section 17a. Any suitable fastening members may be employed for holding the sections in their respective positions. Each unit or trough section contains a screw as at 29 and 30, which screws serve to advance the fuel through the stoker conveyor to a transfer conveyor 31 leading forwardly from the tender. The rearward end of the transfer conveyor 31 is universally connected at 31a to the forward end of the delivery or forward trough section 27. A crusher 32 mounted over the forward end portion of the screw 30 cooperates with the screw to break down lumps of fuel too large for firing. The screws 29, 30 are of substantially the same length which is not in excess of that determined by practice to operate satisfactorily without bending or breaking and such that requires no bearings intermediate the ends of the screw. In longer tenders more than two separate screws may be found necessary. The use of the separated screws is made possible by the provision of the trough sections disposed in different elevations.

60 Suitable means is provided for driving the screws 29 and 30 from their rearward ends. For this purpose a gear drive is mounted at the rearward end of each trough section in housings 33 and 34. The screw 30 is connected to the shaft 35 which carries a gear 36 meshing with the pinion 37 on the pinion shaft 38. This shaft is connected to a power shaft 39 extending forwardly to a prime mover, not shown. The gear shaft 35 extends rearwardly from the housing 34 and is universally connected to the drive shaft 40 which at its rearward end is universally connected to a gear shaft 41. This shaft carries a gear 42 meshing within the housing 33 with a similar gear 43 fixed on the shaft 44 which is operatively connected to the rearward end of the screw 29. Hence, mo-

tion imparted by the power shaft 39 will be transmitted through the gear drives to the screws.

The forms of the invention described above is particularly applicable where it is desired or necessary to form the stoker conveyor in separable sections disposed in the customary conveyor compartment. The use of this construction is made possible by forming the tender with the floor sections disposed in different elevations as heretofore described.

10 Figures 4 to 9 inclusive, illustrate a modification of the invention now to be described. It employs the important feature of the preferred form of the invention, in that the stoker conveyor, mounted beneath the bunker, is composed of sections disposed in different elevations and offset at their adjacent ends. In this modified form the conveyor sections are formed as an integral structure mounted beneath the fuel bunker in the water compartment of the tender. By reason of forming the sections as an integral unit and placing the unit in the water compartment, a compact structure is provided such that in many instances it will not be necessary to construct the floor of the bunker of sections disposed in different elevations as in the preferred form of the invention.

20 Referring to the aforesaid figures, the improved tender is represented as a whole at B. Above the water bottom underframe 45, the fuel bunker 46 and the water compartment 46a are separated by side partition plates 47 and the rear plate 48 secured at their lower marginal edges in any suitable manner to the stoker conveyor indicated generally at 49. The conveyor is an integral unit mounted in the water compartment to contact the water therein and arranged to provide for passage of water from one side of the tender to the other. It may be cast integral with the underframe but preferably, it is built as a separate cast unit mounted on the frame. The forward end of the conveyor unit 49 is formed in any desired manner with the front wall of the tender to form a closure for the water compartment.

25 Like in the preferred form of the invention, the stoker conveyor is composed of a plurality of sections. The rearward section 50 is positioned in a horizontal plane in a level above the receiving end of the forward section 51, which is inclined forwardly from a point below the delivery end of the rearward section. A wall 52 unites the adjacent ends of the rearward and forward sections. Each section is made in the form of a trough opening upwardly to communicate with the fuel bunker. Discharge of fuel from the bunker in to either trough section is controlled by a series of slidable 30 plates 53 positioned horizontally in the seat 54 formed along the upper marginal edges of the trough sections. These plates are pulled forward successively as the coal recedes in the tender to provide as in the preferred form of the invention, a shiftable opening as at 55 through which the fuel passes from the bunker in to the stoker conveyor. The integral conveyor unit 49 carries laterally extending ledges 56 which in effect form a floor for the fuel bunker which floor is apertured 35 as at 57 immediately above the trough formations of the conveyor unit.

30 The conveyor screws 58 and 59 of substantially the same length are mounted respectively in the trough sections 50 and 51. The forward end of 70 screw 58 extends over and above the rearward end of the screw 59 whereby the fuel conveyed along the rearward trough section 50 will be discharged downwardly in to the receiving end portion of the forward trough section 51 on to the 75

screw 59 which advances the same forwardly beyond the crusher 60 to any suitable mechanism for transferring the fuel from the tender to the locomotive, not shown.

5 The screws 58 and 59 are driven from their rearward ends by gearing disposed in a water tight housing 61 formed at the rearward end of the stoker conveyor 49 and extending downwardly through the underframe 45. A bracket structure indicated as a whole at 62 mounted underneath the underframe and extending to one side thereof forms a laterally extending continuation of the housing 61 and opening through a side of the tender. The bracket structure carries the prime mover or stoker drive engine 63. An endless chain 64 imparts motion from the prime mover to a sprocket 66 on the pinion shaft 67. This shaft carries a pinion 68 in mesh with the drive gear 69 on the shaft 70 which is operatively connected to the rearward end of the screw 58. Another pinion 71 is also carried by the pinion shaft 67, which last named pinion engages the gear 72 fixed on the drive shaft 73 which extends forwardly to a point within the forward trough section 51 where it is connected by a universal joint 74 to the rearward end of the screw 59. The aforesaid gears and pinions are journalled in a box 75 which is mounted on the rear transverse wall 76 of the stoker conveyor unit 49 in a manner to form a water tight sleeve therewith. A bearing 77 carried by the wall 52 supports the forward end of the drive shaft 73. This shaft is protected from the water of the water compartment by the sleeve 78 which surrounds the shaft and extends between the wall 52 and the rear wall 76.

40 From the foregoing description it will be recognized that the screws 58 and 59 are driven from their rearward ends by the prime mover and the gear drive both of which are mounted in the water tight housing 61 at the rear of the conveyor unit.

45 In order to deliver the fuel at a point forward of the joint 74 in the forward trough section 51 a removable floor member 80 is provided as an overhanging extension of the rearward trough section 50. This floor member may be held in position by welding or any other suitable means.

50 While the two trough sections are shown as formed in an integral unit, it will be understood that they may be formed separately as in the preferred form of the invention or in any other desired manner such that will serve to arrange the sections whereby the delivery end of the rearward trough section is disposed above the receiving end of the forward trough section at a point beneath the fuel bunker. Various other changes and modifications of the invention may be made without departing from the scope of the 55 appended claims.

60 I claim:

65 1. A locomotive tender of the class described having a fuel bunker provided with an apertured floor constituted by a plurality of apertured sections arranged in different elevations, each section being provided with a plurality of slidable plates for controlling its aperture.

70 2. A locomotive tender of the class described having a fuel bunker with a floor consisting of forward and rearward horizontally disposed sections arranged with the rear section positioned in a level above the forward section, each of said sections being apertured and provided with a plurality of slidable plates controlling the aperture.

75 3. In a locomotive tender of the class described, the combination of a fuel bunker, a floor for said bunker comprising rearward and forward apertured sections disposed in different elevations, and arranged with the forward end of the rearward section positioned adjacent but above the rearward end of the forward section, an upstanding wall interposed between said ends, and a plurality of slidable plates carried by each section for controlling the aperture therein. 10

15 4. In a locomotive tender of the class described, the combination of a fuel bunker, a floor for said bunker comprising rearward and forward apertured sections disposed in different elevations, and arranged with the forward end of the rearward section positioned adjacent but above the rearward end of the forward section, an upstanding wall interposed between said ends, and a plurality of slidable plates carried by each section for controlling the aperture therein, the 20 forward plate of the rearward floor section having means engaging said upstanding wall when a portion of the plate is moved forward of the wall acting to restrain continued forward movement of the plate. 25

25 5. In a locomotive tender, the combination of a fuel bunker, a floor for said bunker comprising rearward and forward apertured sections disposed in different elevations and arranged with the forward end of the rearward section positioned adjacent but above the rearward end of the forward section, an upstanding wall interposed between said ends, a stoker conveyor beneath said floor comprising a conveyor section under each floor section arranged with the forward end of the rearward conveyor section being disposed above and discharging into the rearward end portion of the forward conveyor section, and slidable plates for controlling the passage of fuel from the bunker into the conveyor 30 sections through the apertured floor sections. 35

35 6. In a locomotive tender, the combination of a fuel bunker, a floor for said bunker comprising rearward and forward apertured sections disposed in different elevations and arranged with the forward end of the rearward section positioned adjacent but above the rearward end of the forward section, an upstanding wall interposed between said ends, a stoker conveyor beneath said floor comprising a conveyor section under each floor section arranged with the forward end of the rearward conveyor section being disposed above and discharging into the rearward end portion of the forward conveyor section at a point rearward of said upstanding wall, and 40 slidable plates for controlling the passage of fuel from the bunker into the conveyor sections through the apertured floor sections. 45

45 7. In a locomotive tender, the combination of a fuel bunker, a floor for said bunker comprising rearward and forward apertured sections disposed in different elevations and arranged with the forward end of the rearward section positioned adjacent but above the rearward end of the forward section, a stoker conveyor beneath 50 the floor extending under the aperture of said floor sections, each section being provided with a plurality of slidable plates for controlling the passage of fuel through the aperture of each floor section into the stoker conveyor. 55

55 8. In a locomotive tender, the combination of a fuel bunker, a floor for said bunker comprising rearward and forward apertured sections disposed in different elevations, each section being provided with a plurality of slidable plates for 60

controlling its aperture and a stoker conveyor mounted in communication with the aperture of both sections.

9. In a locomotive tender, the combination of a fuel bunker provided with a plurality of discharge outlets disposed in different elevations, a stoker conveyor section for each discharge outlet, said conveyor sections mounted with the delivery end of one disposed above the receiving end of another, a gear drive for each conveyor section, a drive shaft operatively connecting the gear drives, and a power shaft operatively connected with one of said drives.

10. In a locomotive tender, the combination of a fuel bunker provided with a plurality of discharge outlets disposed in different elevations, a stoker conveyor section for each discharge outlet, said conveyor sections mounted with the delivery end of one disposed above the receiving end of another, a gear drive for each conveyor section, a drive shaft operatively connecting the gear drives, and motion transmitting means associated with one of said drives for imparting motion thereto.

11. In a locomotive tender, the combination of a fuel bunker having a downwardly opening discharge outlet, a stoker conveyor mounted underneath the bunker, said conveyor comprising rearward and forward open mouth trough sections, each of said sections being arranged substantially throughout its length to receive fuel directly from said discharge outlet and disposed within the delivery end of the rearward section offset from the receiving end of the forward section, a screw in each section, and means for driving said screws from their rearward ends.

12. In a locomotive tender the combination of a fuel bunker having a bottom discharge outlet, a stoker conveyor mounted underneath the bunker, said conveyor comprising rearward and forward open mouth trough sections, each of said sections being arranged to receive fuel directly from said discharge outlet and disposed with the delivery end of the rearward section positioned above the receiving end of the forward section, a screw in each section, and means for driving said screws from their rearward ends.

13. In a locomotive tender, the combination of a fuel bunker having a bottom discharge outlet, a stoker conveyor mounted underneath the bunker, said conveyor comprising rearward and forward open mouth trough sections, each of said sections being arranged to receive fuel directly from said discharge outlet and disposed with the delivery end of the rearward section positioned above the receiving end of the forward section, a screw in each trough section, means for driving said sections from their rearward ends, and slid able plates for controlling the passage of fuel from the bunker through its discharge outlet in to each of said troughs.

14. In a locomotive tender, the combination of a fuel bunker having a downwardly opening discharge outlet, a stoker conveyor mounted underneath the bunker, said conveyor comprising rearward and forward open mouth trough sections, each of said sections being arranged to receive fuel directly from said discharge outlet and disposed with the delivery end of the rearward section positioned above the receiving end of the forward section, a screw in each trough section of substantially the same length, and means for driving said screws from their rearward ends.

15. In a locomotive tender, the combination

with a fuel bunker having a downwardly opening discharge outlet, a stoker conveyor mounted underneath the bunker, said conveyor comprising rearward and forward open mouth trough sections, each of said sections being arranged to receive fuel directly from said discharge outlet and disposed with the delivery end of the rearward section positioned above the receiving end of the forward section, a screw in each section, a gear drive operatively connected with the rearward end of the screw in the rearward trough section, a drive shaft connecting said gear drive with the rearward end of the screw in the forward trough section, and means for imparting motion to said gear drive.

16. In a locomotive tender, the combination of a fuel bunker having a downwardly opening discharge outlet, a stoker conveyor mounted underneath the bunker, said conveyor comprising rearward and forward open mouth trough sections, each of said sections being arranged to receive fuel directly from said discharge outlet and disposed with the delivery end of the rearward section positioned above the receiving end of the forward section, a screw in each trough section, the screw in the rearward trough section being disposed in a substantially horizontal plane and the screw in the forward trough section being inclined forwardly from a point below the plane of the screw in the rear trough section, and means for driving said screws from their rearward ends.

17. In a locomotive tender, the combination of a fuel bunker having a downwardly opening discharge outlet, a stoker conveyor mounted underneath the bunker, said conveyor comprising rearward and forward open mouth trough sections, each of said sections being arranged to receive fuel directly from said discharge outlet and disposed with the delivery end of the rearward section positioned above the receiving end of the forward section, a screw in each trough section, the screw in the forward trough section being inclined forwardly from a point below the delivery end of the rearward trough section, and means for driving said screws from their rearward ends consisting of a gear drive operatively connected with the rearward end of the screw in the rearward trough section, a universal joint connected to the rearward end of the screw in the forward section, a drive shaft extending between and operatively connected to said universal joint and said gear drive, and power means for imparting motion to said gear drive.

18. In a locomotive tender, the combination of a fuel bunker and a water compartment, a stoker conveyor mounted in the water compartment in contact with the water therein and being in communication with the fuel bunker, said conveyor comprising rearward and forward trough sections disposed with the delivery end of the rearward section positioned above the receiving end of the forward section, a screw in each trough section, a water tight housing formed at the rear of said rearward trough section, a sleeve extending between said housing and the rearward end of said forward trough section and being open at its one end into said housing and at its other into said forward trough section, a gear drive mounted in said housing and being operatively connected with the screw of the rearward trough section, a drive shaft extending from said gear drive through said sleeve and at its forward end being operatively connected with the screw in said forward

trough section, and means for imparting motion to said gear drive.

19. In a locomotive tender, the combination of a fuel bunker and a water compartment, a stoker conveyor mounted in the water compartment to contact the water therein and being in communication with the fuel bunker, said conveyor comprising rearward and forward sections arranged with the delivery end of the rearward section positioned above the receiving end of the forward section, a screw in each section, an upstanding wall between the adjacent ends of the sections, a bearing mounted in said wall, a water tight housing located at the rearward end of said rearward section, a sleeve extending between said housing and said wall, said sleeve at its one end opening into the housing and at its other end surrounding one end portion of said bearing, a gear drive in said housing connected with the rearward end of the screw in the rearward section, a drive shaft mounted within said sleeve at its one end being connected with said gear drive and at its other end being positioned in said bearing, a universal joint mounted in the forward section connecting said shaft with the screw therein, and means for imparting motion to said gear drive.

20. In a locomotive tender, the combination of a fuel bunker and a water compartment, a stoker conveyor mounted in the water compartment to contact the water therein and being in communication with the fuel bunker, said conveyor comprising rearward and forward sections arranged with the delivery end of the rearward section positioned above the receiving end of the forward section, a screw in each section, an upstanding wall between the adjacent ends of the sections, a bearing mounted in said wall, a water tight housing located at the rearward end of said rearward section, a sleeve extending between said housing and said wall, said sleeve at its one end opening into the housing and at its other end surrounding one end portion of said bearing, a gear drive in said housing connected with the rearward end of the screw in the rearward section, a drive shaft mounted within said sleeve at its one end being connected with said gear drive and at its other end being positioned in said bearing, a universal joint mounted in the forward section connecting said shaft with the screw therein, and a motor contained in said housing and being operatively connected with said gear drive.

21. A locomotive tender of the class described having a fuel bunker provided with an apertured floor constituted by a plurality of apertured sections arranged in different elevations, each section being provided with a plurality of slidable plates for controlling its aperture, the respective slidable plates in each of said respective sections being in the same horizontal plane.

22. A locomotive tender of the class described having a fuel bunker with a floor consisting of forward and rearward horizontally disposed sections arranged with the rear section positioned in a level above the forward section, each of said sections being apertured and provided with a plurality of slidable plates controlling the aperture, the slidable plates in said rearward section lying in the same horizontal plane and the slid-
able plates in said forward section lying in the same horizontal plane.

23. In a locomotive tender, the combination of a fuel bunker, a floor for said bunker comprising rearward and forward apertured sections disposed in different elevations, and a conveyor sec-

tion beneath each floor section, the adjacent ends of said conveyor sections being disposed in different elevations.

24. In a locomotive tender, the combination of a fuel bunker, a floor for said bunker comprising rearward and forward apertured sections disposed in different elevations with the rearward section arranged at a higher elevation than the forward section, and a conveyor section beneath each floor section, the conveyor section beneath the rearward floor section being disposed at a higher elevation than the conveyor section beneath the forward floor section.

25. In a locomotive tender, the combination of a fuel bunker, a floor for said bunker comprising rearward and forward apertured sections, disposed in different elevations and arranged with the forward end of the rearward section positioned adjacent but above the rearward end of the forward section, a conveyor section beneath each floor section arranged with the forward end of the rearward conveyor section being disposed above and discharging into the rearward end portion of the forward conveyor section, and slidable plates for controlling the passage of fuel from the bunker into the conveyor sections through the apertured floor sections.

26. In a locomotive tender, the combination of a fuel bunker, a floor for said bunker comprising a plurality of substantially horizontal apertured sections disposed in different elevations, and a substantially horizontal conveyor section beneath each floor section, the adjacent ends of said conveyor sections being disposed in different elevations.

27. In a locomotive tender, the combination of a fuel bunker, a floor for said bunker comprising rearward and forward substantially horizontal apertured sections disposed in different elevations with the rearward section arranged at a higher elevation than the forward section, and a substantially horizontal conveyor section beneath each floor section, the conveyor section beneath the rearward floor section being disposed at a higher elevation than the conveyor section beneath the forward floor section.

28. In a locomotive tender having a base, a water storage compartment and a fuel bunker, a stoker trough in communication with the fuel bunker and disposed within said compartment so that water will be in contact with the sides and bottom of the trough, the rearward portion of the bottom wall of said trough being spaced a greater distance above said base than the forward portion thereof, the adjacent ends of said rearward and forward bottom wall portions being connected by an upstanding wall, a compartment at the rear of said trough for housing stoker drive mechanism and a water tight casing in said water compartment extending longitudinally beneath the rearward bottom wall portion of said trough and above said base and communicating at one end with said drive housing compartment and at its other end communicating with said trough through an opening in said upstanding wall.

29. As a new article of manufacture, a conveyor trough comprising a rear wall, a front wall, sidewalls and an irregularly shaped bottom wall, said irregularly shaped bottom wall being formed by a transverse upstanding wall portion between said rear and front walls, a rearward bottom wall portion extending from the upper edge of said transverse wall portion to said rear wall and a forward bottom wall portion extending from the lower edge of said transverse wall portion to said

front wall, a transversely extending flange depending from the juncture of said rear wall and said rearward bottom wall portion, said flange and said transverse wall portion each having an opening therethrough and a tubular casing extending longitudinally beneath the rearward bottom wall portion of the trough connecting said openings.

30. As a new article of manufacture, a conveyor trough comprising a rear wall, a front wall, sidewalls and a bottom wall V-shaped in cross section, said bottom wall being formed by a plurality of integrally formed sections including a transverse upstanding section between said rear and front wall, a rearward section extending horizontally from the upper edge of said transverse section to said rear wall and a forward section extending forward and upwardly from the lower edge of said transverse section to said front wall, the front wall of said trough having an opening therethrough, a transversely extending flange depending from the juncture of said rear wall and said bottom wall rearward section, said flange and said bottom wall transverse section each having an opening therethrough and a tubular casing extending longitudinally beneath said bottom wall rearward section connecting said openings.

31. In a locomotive tender, the combination of a fuel bunker having a downwardly opening discharge outlet, a stoker conveyor mounted underneath the bunker, said conveyor comprising rearward and forward sections, each of said sections being open to receive fuel directly from said discharge outlet and disposed with the delivery end

of the rearward section offset from the receiving end of the forward section, a screw in each section, and means for driving said screws from their rearward ends.

32. In a locomotive tender, the combination of a fuel bunker having a downwardly opening discharge outlet, a stoker conveyor mounted underneath the bunker to receive fuel from said outlet, said conveyor comprising rearward and forward conduit sections rigidly mounted with respect to each other and arranged with the delivery end of the rearward section offset from the receiving end of the forward section, a screw in each section, means for driving said screws from their rearward ends, and a transfer conveyor leading forward from the tender, at its rearward end being movably connected to said forward conduit section.

33. In a locomotive tender, the combination of a fuel bunker having a downwardly opening discharge outlet, a stoker conveyor mounted underneath the bunker to receive fuel from said outlet, said conveyor comprising rearward and forward conduit sections rigidly mounted with respect to each other and arranged with the delivery end of the rearward section offset from the receiving end of the forward section within the confines of the tender, a screw in each section, means for driving said screws from their rearward ends, and a transfer conveyor leading forward from the front end of said stoker conveyor, at its rearward end being movably connected to said forward conduit section.

WILLIAM C. PEYTON.

CERTIFICATE OF CORRECTION.

Patent No. 2,029,297.

February 4, 1936.

WILLIAM C. PEYTON.

It is hereby certified that error appears in the printed specification of the above numbered patent requiring correction as follows: Page 2, first column, line 2, for "its" read it; page 4, first column, line 33, claim 11, for "within" read with; and that the said Letters Patent should be read with these corrections therein that the same may conform to the record of the case in the Patent Office.

Signed and sealed this 12th day of May, A. D. 1936.

Leslie Frazer

(Seal) Acting Commissioner of Patents.
